(57) **CLAIM**

The ornamental design for an outdoor mat, as shown and described.

DESCRIPTION

FIG. 1 is an enlarged partial perspective view of FIGS. 6-8 showing our new design, sections of the outdoor mat are shown broken away to more clearly illustrate the details of the design;

FIG. 2 is a plan view of FIG. 1

FIG. 3 is a front elevational view of FIG. 1, the opposite side being a mirror image;

FIG. 4 is a right side view of FIG. 1, the left side view being a mirror image;

FIG. 5 is an enlarged cross-sectional view taken across line 5-5 in FIG. 1;

FIG. 6 is a perspective view of a first embodiment thereof; FIG. 7 is a top plan view of a second embodiment thereof; and,

FIG. 8 is a top plan view of a third embodiment thereof. The bottom of the mat is unadorned and forms no portion of the claimed design.
